CLAIM

The ornamental design for a wood-type golf club head, as shown and described.

DESCRIPTION

FIG. 1 is a perspective view of a wood-type golf club head showing my new design;

FIG. 2 is a rear elevational view thereof;

FIG. 3 is a front elevational view thereof;

FIG. 4 is a toe end elevational view thereof;

FIG. 5 is a heel end elevational view thereof;

FIG. 6 is a bottom plan view thereof;

FIG. 7 is a top plan view thereof;

FIG. 8 is a perspective view of a second embodiment of the golf club head as disclosed in FIG. 1;

FIG. 9 is a rear elevational view of FIG. 8;

FIG. 10 is a front elevational view of FIG. 8;

FIG. 11 is a toe end elevational view of FIG. 8;

FIG. 12 is a heel end elevational view of FIG. 8;

FIG. 13 is a bottom plan view of FIG. 8;

FIG. 14 is a top plan view of FIG. 8;

FIG. 15 is a perspective view of a third embodiment of the golf club head as disclosed in FIG. 1;

FIG. 16 is a rear elevational view of FIG. 15;

FIG. 17 is a front elevational view of FIG. 15;

FIG. 18 is a toe end elevational view of FIG. 15;

FIG. 19 is a heel end elevational view of FIG. 15;

FIG. 20 is a bottom plan of FIG. 15; and

FIG. 21 is a top plan view of FIG. 15;

FIG. 22 is a perspective view of a forth embodiment of the golf club head as disclosed in FIG. 1;

FIG. 23 is a rear elevational view of FIG. 22;

FIG. 24 is a front elevational view of FIG. 22;

FIG. 25 is a toe end elevational view of FIG. 22;

FIG. 26 is a heel end elevational view of FIG. 22;

FIG. 27 is a bottom plan view of FIG. 22; and,

FIG. 28 is a top plan view of FIG. 22.
